United States Patent Office

Des. 232,939
Patented Sept. 24, 1974

232,939

SPRAY HEAD

Leon M. Levy, Chicago, Ill., assignor to Selfix, Inc.

Filed Oct. 24, 1972, Ser. No. 301,213

Term of patent 14 years

Int. Cl. D23—01

U.S. Cl. D23—35

FIG. 1

FIG. 2

FIG. 3

FIG. 4

FIG. 1 is a side elevational view of a spray head showing my new design;

FIG. 2 is a top plan view thereof;

FIG. 3 is a bottom plan view thereof; and

FIG. 4 is a perspective view thereof.

I claim:

The ornamental design for a spray head, as shown.
